UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAYBOLT STRUCTURE.

1,347,560.

Specification of Letters Patent. Patented July 27, 1920.

Application filed April 30, 1919. Serial No. 293,629.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Staybolt Structures; and we do hereby declare the following to be a full, clear, and exact description 10 of the invention, such as will enable others skilled in the art to which it appertains to make and use the same.

This invention relates to improvements in staybolt structures, one object of the invention being to provide a structure in which the bearing sleeve or member for the spherical or spheroidal head of a staybolt, shall be so mounted in the outer boiler sheet that it will become so disposed as to insure accurate alinement with the bolt opening of the inner boiler sheet when the two boiler sheets are disposed at an angle to each other or when the openings in parallel boiler sheets are not in accurate alinement, and to 20 provide means whereby the bearing member may be secured in the position in which it may be set or adjusted.

With this and other objects in view, the invention consists in certain novel features 30 of construction and combinations of parts as hereinafter set forth and pointed out in the claims.

In the accompanying drawings; Figure 1 is a sectional view illustrating an embodiment 35 of our invention, and Figs. 2 and 3 are similar views showing certain modifications.

1 represents an inner boiler sheet, and 2 an outer boiler sheet such, for example, as 40 the roof sheet which is disposed at an angle to said inner sheet.

The outer or roof sheet 2 is made with 45 openings, each of which may be tapering,—viz. made larger at the outer end than at the inner end. The wall 3 of opening 2 may be curved transversely and constitutes a bearing or socket seat in the boiler sheet for a partly spherical or spheroidal sleeve or bushing 4 so that the latter shall be capable 50 of universal movement,—the connection of the sleeve or bushing member with the boiler sheet thus being of the ball-and-socket type. The partly spherical sleeve or bushing is

made with an opening 5 therethrough which is of greater diameter at its outer than at 55 its inner portion, and a portion of the wall of said opening is curved in a manner to form a partly spherical bearing 6 for the curved or spheroidal head 7 at the outer or upper end of a staybolt 8, said sleeve or 60 bushing thus constituting a bearing member for the bolt head. The other or inner end of the staybolt may be threaded to pass through the inner boiler sheet 1 and this inner end of the staybolt may be upset against 65 the inner boiler sheet, as shown at 9.

The outer or upper portion of the partly spherical sleeve or bushing member 4 is threaded interiorly as at 10 to receive the external threads of a cap or closure 11 having an angular portion 12 to receive a wrench. The inner portion of the cap or closure 11 may be recessed to provide an adequate clearance space 13 between the bolt head and the cap. 75

When the partly spherical bearing sleeve or bushing shall have become properly set or adjusted, said sleeve or bushing will be welded to the boiler roof sheet 2 with the use of a welding alloy (as indicated at 14) 80 which is located around said sleeve or bushing in a manner to become welded to the same and to the boiler roof sheet and to enter any recess (as at 15) which may occur between the outer face of said sleeve 85 or bushing and the edge of the opening in the boiler sheet, said sleeve being thus intimately united to the boiler sheet.

In the form of the invention shown in Fig. 2, the head 7^a of the staybolt is made 90 more nearly spherical than the bolt head 7 shown in Fig. 1. In the construction shown in Fig. 2, the opening through the partly spherical bearing sleeve or bushing 4^a is made slightly tapering with the curved seat 95 4^b for the bolt head at its lower end and said sleeve or bushing 4^a is made with an annular flange or extension 16 which is internally threaded as at 17 to receive an externally threaded closure 18. This closure may be 100 provided with a flange 20 to overlie the annular flange or extension 16.

In the construction shown in Fig. 3 the sleeve or bushing indicated at 21 has a general tapering shape with the bearing for the 105 bolt head 7^b in its lower curved or partly

spherical portion 22. In this form, the wall of the opening 23 in the boiler roof or sheet is not made concave or partly spherical but the sleeve can turn to become properly aligned, on the convex outer portion 24 of the wall of the opening in the boiler sheet, and the sleeve is secured by a weld 25 to the boiler sheet.

In Fig. 3, a closure 19 is shown screwed into the sleeve and adapted to seat on a shoulder 19^a therein.

By the term "transversely" in describing the curvature of the wall of the opening in the boiler sheet, is intended to mean that said wall is curved in a direction extending from one face of the sheet toward the other face, and the use of the term "tapering" in describing the opening in the boiler sheet is intended to describe an opening which has greater diameter at one end than at the other.

Other changes might be made in the details of construction of our invention without departing from the spirit thereof or limiting its scope and hence we do not wish to restrict ourselves to the precise details herein set forth.

Having fully described our invention what we claim as new and desire to secure by Letters-Patent, is:—

1. In a staybolt structure for boilers, the combination with a boiler sheet provided with an opening, of a sleeve or bushing adapted to have initial universally movable mounting in said opening and having an interior bearing for the head of a staybolt, a staybolt having a head mounted on the interior bearing of said sleeve or bushing and means for securing said sleeve or bushing to the boiler sheet.

2. In a staybolt structure for boilers, the combination with a boiler sheet provided with an opening, of a sleeve or bushing adapted to have initial universally movable mounting in said opening and having an interior bearing for the head of a staybolt, a staybolt having a rounded head mounted on the interior bearing of said sleeve or bushing, and a welded connection securing said sleeve or bushing to the boiler sheet.

3. In a staybolt structure for boilers, the combination with a boiler sheet having an opening provided with a transversely curved wall, of a spheroidal sleeve having a mounting on said transversely curved wall, said sleeve or bushing having a bearing therein for the curved head of a staybolt, and a staybolt having a rounded head mounted on said bearing in the sleeve or bushing.

4. In a staybolt structure for boilers, the combination with a boiler sheet having an opening provided with a transversely curved wall, of a spheroidal sleeve or bushing mounted on said transversely curved wall,

said sleeve or bushing having an interior bearing for the curved head of a staybolt, a staybolt having a curved head mounted on said bearing in the sleeve or bushing, and a weld securing said sleeve or bushing to the boiler sheet.

5. In a staybolt structure, the combination with a boiler sheet having an opening, of a spheroidal member mounted in said opening and having an opening therethrough larger at one end than at the other, said spheroidal member also having therein a bearing for the head of a staybolt, and a weld securing said spheroidal member to the boiler sheet.

6. In a staybolt structure, the combination with a boiler sheet having a tapering opening therein, of a bearing member having an initial universally adjustable mounting in said tapering opening, said member having an internal bearing for the head of a staybolt, a staybolt having a head mounted in said bearing member, and a weld securing said member in adjusted position to the boiler sheet.

7. In a staybolt structure for boilers, the combination with a boiler sheet having an opening, of a spheroidal member adapted to have initial universally movable mounting in said opening, said spheroidal member having an opening therethrough which is larger at one end than at the other and also having a bearing for the head of a staybolt, a staybolt having a head mounted on the bearing within said spheroidal member, and a closure closing the larger end of the opening in said spheroidal member.

8. In a staybolt structure, the combination with a boiler sheet provided with an opening having a transversely curved wall, of a spheroidal member mounted on said transversely curved wall, said spheroidal member having an opening therethrough which is larger at one end than at the other and also having an interior bearing for the rounded head of a staybolt, a staybolt entering said spheroidal member and having a rounded head mounted on the bearing therein, a closure closing the larger end of the opening in said spheroidal member, and a welded connection between said spheroidal member and the boiler sheet.

9. In a staybolt structure, the combination with a boiler sheet having a socket seat, of a spheroidal sleeve mounted in said socket seat whereby a ball-and-socket connection is afforded between said sleeve and the boiler sheet, the said spheroidal sleeve having an opening larger at one end than at the other end and having therein a bearing for the head of a staybolt, and a staybolt entering said sleeve and having a head mounted on the bearing therein, and means for securing said spheroidal sleeve to the boiler sheet.

10. In a staybolt structure, the combina-

tion with a boiler sheet having an opening, of a spheroidal sleeve entering said opening and having a bearing for a bolt head, and means for securing said spheroidal sleeve 5 to a boiler sheet.

11. In a staybolt structure, the combination of a boiler sheet having an opening, of a spheroidal sleeve having therein a bearing for a bolt head, said sleeve entering the opening 10 in the boiler sheet, and a weld securing said spheroidal sleeve to the boiler sheet.

12. In a staybolt structure, the combination with two boiler sheets, one of said sheets having an opening therein, of a spheroidal 15 sleeve adapted to have initial universal mounting in said opening in the boiler sheet, said sleeve having an internal bearing for the head of a staybolt, a staybolt having a head mounted on said internal bearing, 20 means securing the other end of the staybolt to the adjacent boiler sheet, and means securing said spheroidal sleeve to the boiler sheet in which it is mounted.

13. In a staybolt connection for boilers, 25 the combination of a boiler sheet having an opening with a curved or rounded wall, and a curved or rounded sleeve mounted in said opening and supported on said curved or rounded wall of the same, the said sleeve 30 being secured to the boiler sheet by welding.

14. In a staybolt connection for boilers, the combination of a boiler sheet having an opening, a sleeve adapted to have initial universally movable mounting in said opening, and means for securing said sleeve to 35 the boiler sheet, said means consisting of a

welded connection between the sleeve and the boiler sheet.

15. In a staybolt structure, the combination with boiler sheets, one of said sheets 40 having a socket seat, of a sleeve of tubular form and having a curved outer portion mounted on said socket seat, said sleeve having a seat therein for the rounded head of a staybolt, a staybolt having a rounded head 45 mounted on the seat within said sleeve, means for capping the sleeve, means for securing the sleeve to the boiler sheet in which it is mounted and means securing said bolt to the other boiler sheet. 50

16. In a staybolt structure, the combination with a boiler sheet having an opening, of a sleeve having a ball-and-socket connection with the boiler sheet at the opening 55 therein and having an internal bearing for the head of a staybolt.

17. A bearing sleeve for the head of a staybolt, having an exterior curved portion forming a seat whereby said sleeve may have universal adjustment in a boiler sheet, and 60 said sleeve having an internal seat whereby the head of a staybolt may be mounted therein.

In testimony whereof we have signed this specification in the presence of two subscr- 65 ing witnesses.
